UNITED STATES PATENT OFFICE.

RICHARD FLEMING, OF LYNN, MASSACHUSETTS, ASSIGNOR TO GENERAL ELECTRIC COMPANY, A CORPORATION OF NEW YORK.

CIRCUIT-CONTROL APPARATUS.

No. 868,165.

Specification of Letters Patent.

Patented Aug. 13, 1907.

Application filed December 5, 1905. Serial No. 290,410.

To all whom it may concern:

Be it known that I, RICHARD FLEMING, a citizen of the United States, residing at Lynn, county of Essex, State of Massachusetts, have invented certain new and useful Improvements in Circuit-Control Apparatus, of which the following is a specification.

My present invention relates to apparatus in which are employed relatively movable contacts, the engagement and disengagement of which are relied upon to control an electric circuit or circuits.

My invention is peculiarly adapted for embodiment in an electromagnetic relay device. One embodiment of my invention in such a device I have herein-after illustrated and described in detail. It will be obvious, however, that my invention is not limited for its utility to employment with the apparatus of which I have shown it as forming a part.

The various features of novelty which characterize my invention are pointed out with particularity in the claims annexed to and forming a part of this specification.

For a better understanding of the nature of my invention and the advantages possessed by it, reference may be had to the accompanying drawings and descriptive matter in which I have illustrated somewhat in detail one of the forms in which my invention may be embodied.

Of the drawings, Figure 1 is an elevation with parts broken away and in section of an automatic relay device; Fig. 2 is an elevation at right angles to Fig. 1 and partly in section on the line 2 2 thereof; and Fig. 3 is a diagram illustrating an arrangement in which my invention may be employed in regulating the voltage of an alternating current-distribution system.

In the drawings, 1 represents a base or support upon which is mounted a casing 2 in which my relay device is mounted. The relay device proper comprises two pairs of stationary coils 3 and 4 and a pair of movable coils 5 and 6. As shown, the coil 5 is between and in axial alinement with the coil 3. Similarly the coil 6 is between and in axial alinement with the coil 4. The coils 5 and 6 are supported by a frame or member 7 pivotally mounted on bearing pins 8. An adjustable counter weight 9 mounted on a horizontal arm 10 secured to the member 7 normally tends to turn the frame 7 in the direction indicated by the arrow in Fig. 1.

A threaded rod 11 projecting vertically upward from the center of the member 7 carries at its upper end a clamp 12 in which is secured a contact member 13 in the form of a transversely extending conducting rod which may be of carbon or graphite. Contact members 14 and 15 which may also be in the form of

rods or pencils of conducting material such as carbon or graphite are supported in alinement with the member 13 but at opposite ends thereof, by means of spring supporting devices 16 and 17, respectively.

The spring supporting device 16 is in the form of a U-shaped strip of resilient conducting metal, the legs of which are of unequal length. Near the end of the longer leg is secured a clamp 14' in which is secured the contact member 14. To the end of the other leg is secured a slotted plate 16' which is adjustably secured to the terminal member 18. To the extreme upper end of the long leg of the member 16 is secured an armature 19 of magnetic material. Insulation 20 covers the face of the armature 19. The member 17 which is similar to the member 16, is provided with a clamp 15', slotted plate 17' adjustably secured to the terminal 21, armature 22, and insulation 23. These parts correspond to the parts 14', 16', 19 and 20 respectively. The armatures 19 and 22 face opposite ends of the core 24 of an electromagnet 25.

In Fig. 3 I have illustrated the use of my present invention in connection with arrangements for regulating current circuits such as are described and claimed in my Patents 783,513 and No. 783,514 of February 28, 1905. In this use of my invention 31 and 32 represent conductors conveying current from a source of alternating current 33 to the translating devices 34. The conductor 32 has connected in series with it a movable coil 35, which cooperates with a pair of stationary coils 36 and 37. The coils 36 and 37 are in alinement with each other and are connected 85 between the conductors 31 and 32 so that their magnetizing effects are in opposite directions. When the coil 35 is in position relative to the coils 36 and 37, shown in Fig. 3, the coils 35 and 37 will, if properly connected, have the effect of increasing the voltage 90 supplied to the translating device. In this position of the apparatus the coil 36 has practically no effect upon the voltage between the conductors 31 and 32. When the coil 35 surrounds the coil 36 the effect is then to decrease the voltage. At an intermediate 95 position the effect of the coils may be nil. The coil 38 forms a closed circuit tending to reduce the inductance of the coil 35 when it surrounds the coil 33.

The coils 3, 4, 5 and 6 are in series with each other and are connected to the terminals of a winding 39 in 100 inductive relation with the winding 40 the terminals of which are connected to conductors 31 and 32 at points which may be more or less closely adjacent the translating devices 34. When the voltage between the terminals of the winding 39 corresponding to that 105 between the lines 31 and 32 is below a predetermined

- amount, the rod 11 is moved in the direction indicated by the arrow through the action of the counter-weight 9 (not shown in Fig. 3). When the voltage increases beyond a predetermined amount, however, 5 the action of the coils 3 and 4 on the coils 5 and 6 causes the rod 11 to be swung in the opposite direction. 41 represents a valve controlling the flow of suitable working fluid such as compressed air from the reservoir 42 to apparatus for producing relative movement 10 between coil 35 and coils 36 and 37. The valve 41 is provided with an armature 42 located between the ends of the core of electromagnets 43 and 44. The electromagnets 43 and 44 are normally energized alike from a suitable source of current 45 through a circuit 15 comprising conductors 46, 47 and 48 which connect the windings of the electromagnets in series with each other and a source of current 45. As shown the member 16 is electrically connected to the conductor 46 and the member 17 is electrically connected to the conductor 48. A conductor 49 leads from the conductor 47 to one terminal of the electromagnet 25. The other terminal of the electromagnet 25 is connected by a flexible conductor 50 to the member 11 and thereby with the contact member 13. 20 An apparatus for raising and lowering the movable coil 35 is shown diagrammatically in Fig. 3. It comprises a cylinder 51 fitted with a movable plunger or piston 52 carrying at its top a cross bar 53 from which the movable coil 35 is suspended by cords 54. The 25 spaces below and above the piston are connected respectively with the compressed air valve 41 by pipes 55 and 56. The valve 41 is illustrated diagrammatically, but is of a common type. When the movable armature 42 is in the mid position as shown, air is cut 30 off from pipes 55 and 56, but when the armature moves toward coil 44 air is admitted to pipe 55 and is released from pipe 56 from whence it discharges through an exit pipe 57. Air admitted through pipe 55 raises piston 52 and consequently the coil 35. 35 When the voltage between the lines 31 and 32 is below a predetermined amount, the arm 11 moves in the direction of the arrow to bring about an engagement between the contacts 13 and 14. This short circuits the winding of the electromagnet 43 where- 40 upon the armature 42 will be attracted by the core of the electromagnet 44. This will, through the valve 41, allow the operating fluid from the reservoir 42 to cause an operation of the coil moving mechanism which will change the relative position between the 45 coil 35 and the coils 36 and 37 in such a manner as to raise the voltage between the lines 31 and 32. Similarly when the potential between the lines 31 and 32 rises above a predetermined amount, the contact members 13 and 15 will engage and by short circuiting the 50 winding of the electromagnet 44 will cause the armature 42 to be attracted by the electromagnet 43, thus causing an opposite movement between the coil 35 and the coils 36 and 37. 55 Whenever the contact member 13 engages either 60 contact 14 or the contact 15, the coil 25 will become operatively energized, thus attracting the armatures 20 and 22. As these armatures move toward the core, the member 11 will thereby be moved back toward its vertical position. This tends to prolong somewhat

the period of engagement between the contact member 65 13 and the particular contact device 13 or 14 with which it is in engagement while at the same time producing a slight relative transverse movement between the surfaces of the contact member in engagement, which tends to prevent any arcing action which may 70 occur between them from causing them to stick or weld together.

While the form of my invention hereinbefore described and illustrated in detail has given excellent results in practice it will be obvious that changes 75 10 may be made in the form of the invention disclosed, without departing from its spirit, and I do not wish the claims hereinafter made to be limited to the particular embodiment of my invention disclosed, more than is made necessary by the state of the art.

What I claim as new and desire to secure by Letters Patent of the United States, is,—

1. In combination, a pair of normally stationary contact members, a floating contact between said normally stationary members engaging one or the other of said stationary members on reaching the limit of its movement in the one direction or the other, and electromagnetic means for causing said normally stationary members to be moved toward each other upon such engagement.

2. In combination, a pair of flexibly supported normally 90 stationary contact members, a floating contact between said normally stationary contacts, and electromagnetic means for moving said normally stationary members toward each other whenever the floating contact engages either of them.

3. In combination, a pair of resilient members, each supporting an armature of magnetic material and a contact member, and electromagnetic devices between the armatures and arranged to attract both of them when energized, a floating contact between the contacts supported 100 on the resilient members and arranged to engage one or the other of said contacts when it approaches one or the other limits of its movements, and means for energizing said electromagnet when such contact takes place.

4. In combination, a pair of contact members, a floating 105 contact movable from a position in which it engages one of said members to a position in which it engages the other of said members, and electromagnetic means energized by the engagement of the contact with either member for producing a relative movement between the contact 110 and member during such engagement.

5. In combination, a pair of flexibly supported normally 115 stationary contact members, an armature connected to each of said members, an electromagnetic device arranged to attract both of said armatures when energized, a floating contact, means for moving it from a position in which it engages one of the resiliently supported contacts to a position in which it engages the other of the resiliently supported contacts, and means for energizing said electromagnet when either engagement takes place.

6. In combination, a pair of normally stationary contact members, a floating contact movable from a position in which it engages one of said members to a position in which it engages the other of said members, and means automatically actuated by either of such engagements for 125 prolonging the period of engagement.

7. In combination, a pair of normally stationary contact members, a floating contact between said normally stationary contacts engaging one or the other of them on reaching the limit of its movement in one direction or the 130 other, and electromagnetic means energized by such engagement for causing said normally stationary contacts to be moved toward each other upon such engagement.

8. In a circuit regulating device, a pair of normally stationary contact members, a movable contact member movable from a position in which it engages one of said stationary members to a position in which it engages the other of said stationary members in response to variations in the condition of the circuit regulated, means for varying

the conditions of the circuit to be regulated or controlled by such engagement, and electromagnetic means also controlled by such engagement for prolonging the period of engagement between the movable contact and either of 10
5 said normally stationary contact members.

9. In combination, a pair of contact members, a floating contact movable from a position in which it engages one of said members to a position in which it engages the other of said members, and electromagnetic means energized by

the engagement of the contact with either member for prolonging the period of such engagement.

In witness whereof, I have hereunto set my hand this second day of December, 1905.

RICHARD FLEMING.
